UNITED STATES PATENT OFFICE

WILLIAM O. HICKOK, JR., OF HARRISBURG, PENNSYLVANIA.

DESIGN FOR VAULT-COVERS.

Specification forming part of Design No. 7,388, dated April 21, 1874; application filed March 26, 1874.
[Term of Patent 14 years.]

To all whom it may concern:

Be it known that I, WILLIAM O. HICKOK, Jr., of Harrisburg, in the county of Dauphin and in the State of Pennsylvania, have invented certain new and useful Improvements in Design for Vault-Covers; and do hereby declare that the following is a full, clear, and exact description thereof, reference being had to the accompanying drawings, and to the letters of reference marked thereon, making a part of this specification.

The nature of my design is fully represented in the accompanying drawing, to which reference is made.

A represents a circular piece, surrounded by a five-pointed skeleton star, B, around which is a circle, C. Surrounding the circle C is a five-pointed skeleton star, D, between the points of which are circles E, each containing a five-pointed skeleton star, G. Within the points of the star D are circles *a a*, and the

whole is surrounded by a circular flange, H. The various circles and stars described are not formed of regular straight or continuous lines, but are somewhat irregular, still retaining the general outline of the circles and stars. The open spaces in this casting may or may not be filled with glass, as desired.

This casting is intended for a vault-cover in pavements.

What I claim as my invention is—

The design for vault-covers, consisting of irregular circles and stars, substantially as shown and described.

In testimony that I claim the foregoing I have hereunto set my hand this 17th day of March, 1874.

W. O. HICKOK, JR.
